UNITED STATES PATENT OFFICE.

THOMAS B. KINRAIDE, OF JAMAICA PLAIN, MASSACHUSETTS.

ELECTRIC SPARK-GAP FOR INTERRUPTERS.

No. 884,499.

Specification of Letters Patent.

Patented April 14, 1908.

Application filed April 24, 1906. Serial No. 318,452.

To all whom it may concern:

Be it known that I, THOMAS B. KINRAIDE, a citizen of the United States, residing at Jamaica Plain, in the county of Suffolk and 5 State of Massachusetts, have invented an Improvement in Electric Spark - Gaps for Interrupters, of which the following description, in connection with the accompanying drawings, is a specification, like letters on the 10 drawings representing like parts.

My invention relates to that class of spark gaps or interrupters especially adapted to convey heavy low voltage currents of high frequency such for example as developed by 15 the coil shown in my Patent No. 615653. For instance, in my Patent No. 623318 I have provided opposite plates between whose plane surfaces the sparking takes place, and my present invention aims to maintain the 20 electrodes cool and at the same time prevent permanent oxidizing of their discharge surfaces and thereby prolong their service-ability indefinitely.

To the above end I have provided automatic means for blowing out the spark instantly, said means consisting of interposing automatically between the discharge surfaces an explosive gas or, in other words it 25 consists in causing an explosion simultaneously with the discharge which effectually blows out the flame of the discharge. This explosion, in the preferred embodiment of 30 my invention, is provided by causing a film of water to deposit on the discharge surface or between the two electrodes, said water 35 preferably being maintained at the required point by capillary means. The presence of the water and especially the presence of adjacent bodies of water helps to maintain 40 the electrodes cool and in proper operative condition.

Further details of my invention will be pointed out in the following description taken in connection with the accompanying 45 drawings in which I have shown one embodiment of my invention.

In the drawing, Figure 1 represents in 50 side elevation and vertical section, parts being broken away for clearness of illustration, one form of my invention adapted to operate as an interrupter or vibrator; Fig. 2 is a top plan view thereof. Fig. 3 is an end view of one of the electrodes.

On a suitable base 1 is a cooling box or 55 tank 2 for holding water or other cooling

medium 3, secured to said base by a stud 4 and nuts 5 and having a stopper 6 in its upper side for the admission of the water. In its upper side the cooling box 2 has a central threaded aperture 7 in which is removably mounted a tubular electrode holder 8 provided externally with fine threads 9 and engaged by an adjustable cap 10 for giving an extremely accurate and delicate adjustment to an electrode 11 supported thereby to slide 60 in the holder 8.

The electrode 11 constitutes one of the important features of my invention and is preferably composed of a bunch of copper wires 12, packed tightly in a sheath or retaining 65 envelop 13 and ground off flat at their opposite ends as clearly shown in Fig. 1. I have found that a bunch of copper wires thus bound together, will afford a permanent capillary means for maintaining the electrode 70 constantly filled with enough water to provide the desired amount of moisture at the discharge end of the electrode ready at all times to volatilize and explode when the current passes, thereby blowing out the flame 75 and washing away all oxidation and maintaining the ends of the sparking electrodes clean and in proper operative condition. The bunch of wires might be called a copper wire-wick, and it will be understood that the copper wires may be bound together in any 80 wick-form, provided the desired capillary ducts or passages are provided through the wick or electrode of conductive material to permit the passage of the requisite amount of 85 moisture for volatilizing at the discharge end. It is not necessary that wires as such should be used, as the holes or ducts may be secured in various other ways and in fact the porous condition may be provided in a large variety 90 of ways. The essential feature as to this 95 part of the invention, broadly considered, is to provide the electrode with means for permitting the water or moisture to enter an extremely limited and yet certain, continuous 100 amount at the end of the electrode so as to be present at or between the meeting or discharge ends when the discharge takes place.

The electrode 11 is supported by the adjuster 10 which is provided with an opening 105 or openings 14 for the free admission of water from the surrounding chamber and I prefer to interpose a damper in the form of one or more layers of blotting paper or similar substance 15 for filtering the water through to 110

the end of the electrode for the purpose of limiting the capillary action of the latter and thereby further restricting the amount of water. By carefully regulating the amount 5 of water admitted to the electrode, the products of combustion, *i. e.* the oxid, may be caused to blow out as dry dust or escape as thick paste or thin paste. This will be referred to again later.

- 10 Above the cooling box 2 I provide a similar box 16, provided with a vertical tubular center 17 in which is mounted an electrode 18 which may be similar in construction to the electrode 11. In order to carry the water or 15 other cooling medium 19 as close to the sparking point as possible I provide a depression 20 in the box 16 having a central conical portion 21. Adjacent to this conical portion is a downwardly flaring shield 22 which co- 20 operates with an upwardly extending shield or flange 23 in retaining the products of combustion while yet permitting a free circulation of air. The downwardly extending or overhanging part 22 operates to direct the 25 ashes or products of combustion into the collecting basin formed by the cup-shaped top of the tubular portion 8. The upper portion of the apparatus is mounted on posts 24, the box 16 being provided with ears 25 for this 30 purpose retained by thumb nuts 26. The box 16 has a stopper 27 the same as the stopper 6 of the lower box or cooler, and is provided in the apparatus of the drawings, with an operating device for causing rapid inter- 35 ruptures consisting of a striker 28, springs 29, 30 and cam 31 as shown and explained in my Patent No. 770431. It will be understood that the apparatus may be operated as a spark gap the same as in my Patent No. 623,318, 40 above mentioned. The upper electrode connects by a rod 32 extending through one of the posts 24 with a binding post 33 and the other electrode connects by the stud 4 with a binding post 34.
- 45 One of the chief advantages of my invention is that it enables me to do away with the platinum points which have heretofore been necessary in high speed interrupters. By interposing the automatic blow out or deoxidizer, or moisture carrying electrode it becomes 50 perfectly practicable to use copper electrodes, which has heretofore been impossible in this class of apparatus.
- 55 My invention enables the discharge to be steady and uniform without permitting imperative oxidizing of the electrodes and is especially adapted for currents of low voltage such as used with my flat coil (Patent No. 615653).
- 60 In use the cooling chambers are filled with water which maintains the electrodes cool, the body of water being large so as to keep up a more or less continuous circulation adjacent the discharge ends of the electrodes. At 65 every discharge of current the water which

has seeped through the damper 15 and traveled up the electrode 11 by capillary action, is volatilized and exploded, thereby driving off the products of combustion and maintaining the electrodes clean, so that although the latter are composed of copper or other inexpensive material of low refractory capacity, they maintain a high standard of efficiency. The admission of water is regulated so as to conform to the current used and for desired 70 results, and the electrode is raised or lowered by correspondingly screwing up or down the cap 10.

The electrodes are inexpensive, readily put in place, and capable of long and continued 75 use.

As already stated, I do not intend to limit myself to the precise details of construction herein shown, as a wide variety of embodiments is contemplated, within the spirit and 80 scope of my invention.

Having described my invention, what I claim as new and desire to secure by Letters Patent is,

1. An apparatus of the kind described, 90 comprising opposite discharge electrodes, and means for automatically providing a self-cleaning explosion between them at the moment of current discharge.

2. An apparatus of the kind described, 95 comprising opposite discharge electrodes, and means for interposing a film of moisture between them at the moment of current discharge.

3. An apparatus of the kind described, 100 comprising opposite discharge electrodes, and a supply of fluid adjacent one of said electrodes, said electrodes having capillary means for conveying said moisture to the discharge ends of the electrodes.

4. In an apparatus of the kind described, 105 opposite discharge electrodes, and means for providing a film of moisture at their discharge area for keeping the electrodes clean.

5. In an apparatus of the kind described, 110 an electrode having a multitude of capillary ducts closely arranged therethrough from end to end, said electrode consisting of a bundle of wires extending from one terminal of the electrode to the opposite terminal thereof, and means for binding said wires tightly together, the passages between said wires constituting said ducts.

6. In an apparatus of the kind described, 120 an electrode having a multitude of capillary ducts closely arranged therethrough from end to end, said electrode consisting of a bundle of copper wires extending from one terminal of the electrode to the opposite terminal thereof, and means for binding said copper wires tightly together, the passages between said copper wires constituting said ducts.

7. In a high frequency discharge apparatus, opposite electrodes for discharging heavy 130

currents of low voltage, said electrodes being composed of conductive material of low refractory capacity, and provided with means operated by the current, for automatically 5 cleaning all oxidation and products of combustion from their discharge ends at each discharge of current.

8. In an apparatus of the kind described, opposite water coolers, having central tubular holders, opposite electrodes adjustably mounted in said holders and projecting toward each other therefrom, at their discharge ends between said coolers, and means between said coolers for retaining the products 15 of combustion which fall from between said electrodes.

9. In an apparatus of the kind described, opposite water coolers, having central tubular holders, opposite electrodes adjustably 20 mounted in said holders and projecting toward each other therefrom, at their discharge ends between said coolers, and means between said coolers for retaining the products of combustion which fall from between said 25 electrodes, said means consisting of a cup-shaped receptacle around one electrode and a projecting deflector about the other electrode.

10. In an apparatus of the kind described, 30 a water cooler, a removable tubular holder therein, a cap adjustably secured to the inner end of said holder, said cap being perforated to admit water from the cooler, and a wick-

like electrode mounted in said holder to engage said cap.

11. In an apparatus of the kind described, a water cooler, a removable tubular holder therein, a cap adjustably secured to the inner end of said holder, said cap being perforated to admit water from the cooler, a wick-like 40 electrode mounted in said holder to engage said cap, and a moisture-limiting damper interposed between said electrode and the opening in said cap.

12. In an apparatus of the kind described, 45 a water cooler, a removable tubular holder therein, a cap adjustably secured to the inner end of said holder, said cap being perforated to admit water from the cooler, and an electrode mounted in said holder, said holder 50 having a cup-shaped outer end extending about the projecting end of said electrode.

13. A water cooler, having a depending central portion, a central tube extending up from said depending portion, and an electrode mounted in said central tube, said depending portion having a downwardly flaring deflector about said electrode for diverting the products of combustion.

In testimony whereof, I have signed my 60 name to this specification, in the presence of two subscribing witnesses.

THOMAS B. KINRAIDE.
